UNITED STATES PATENT OFFICE.

WALTER BUZATT, OF BLUE ASH, OHIO, ASSIGNOR TO THE LIPPINCOTT COMPANY, OF CINCINNATI, OHIO, A CORPORATION OF OHIO.

MACHINE FOR SECURING METALLIC CAPS TO BOTTLES.

1,319,845.

Specification of Letters Patent.

Patented Oct. 28, 1919.

Application filed February 19, 1917. Serial No. 149,604.

To all whom it may concern:

Be it known that I, WALTER BUZATT, a citizen of the United States, and residing at Blue Ash, in the county of Hamilton and State of Ohio, have invented a new and useful Improvement in Machines for Securing Metallic Caps to Bottles, of which the following specification is a full disclosure.

My invention relates to a machine for securing caps to bottles, jars and the like, and particularly to a rotatable cap chucking device adapted to embrace and frictionally grip a screw cap to thread the cap upon the jar, or apply a final sealing pressure to the cap when previously applied to the jar.

One of the objects of the invention is to provide a device constantly rotating, and arranged to receive a screw cap while in rotation for applying the cap to the jar or for applying a final sealing pressure to the cap and releasing to any excessive pressure to avoid the breaking of the jars or injury to the caps.

Another object of the invention is to provide a pair of oppositely disposed, rotatable jaws arranged to expand apart for conveniently and quickly receiving a jar screw cap which has been previously inserted on the jar, the jaws embracing the circumferential edge of the cap and frictionally binding therewith to apply a final sealing pressure to the cap.

Another object of the invention relates to means for supporting the jar in an upright position and for moving the jar upwardly and inserting its cap into engagement with cap securing devices, and to certain details of construction, all more fully revealed in the following description of the drawings accompanied herewith, and in the said drawings like characters of reference denote corresponding parts throughout the several views, of which:

Figure 1 is a side elevation of a machine embodying my invention.

Fig. 2 is an enlarged central vertical section of the rotatable screw cap receiving chuck which embraces the cap and frictionally connects therewith for securing the cap to the bottle or applying a final sealing pressure to the cap.

Fig. 3 is a section on line, 3—3 Fig. 2.

Fig. 4 is a bottom plan view of a cap receiving chuck.

Referring to the drawings and particularly to Fig. 1 which illustrates a complete machine organization, an embodiment of frame and transmission devices are included as of general character and design common in machine tools, and provide a means for supporting and rotating the devices for securing a screw cap to a bottle or like container. These parts therefore may represent any design or type of construction adaptable for use in connection with the invention herein disclosed.

1 indicates a column having a base plate extension 2, and a top horizontal bracket extension 3 for receiving a motor 4.

The motor is provided with a pulley which carries a belt 5, connecting and engaged over a pulley 6, journaled upon a bracket 7, extending from the column.

Fixed to the pulley 6, or upon a shaft connecting with the pulley is a second pulley 8, carrying a belt 9, which connects and engages over a pulley 10, at the base of the column. The pulley 10 connects with a shaft not shown, journaled in the bearing 11, fixed to and extended vertically from the base 2.

The shaft connecting with the pulley 10, has a second pulley 12, fixed thereto, carrying a belt 13, which extends upwardly having its forward and return runs passing over a pair of idlers, one idler 14, only being shown, to connect with a pulley 15, journaled upon a vertical shaft, 16, secured within hub or boss formed upon the bracket extension 3, of the column 1. The idlers being solely for the purpose of diverting the belt runs from the vertical to a horizontal line. It is obvious that the transmission elements may be of an arrangement to bring the motor and pulley 15, in a more direct connection.

The devices for securing the screw caps to bottles may be referred to as a chuck as it receives and clamps the cap. It comprises a disk plate 16, dependently suspended from the lower side of the pulley 15, by means of three coupling rods 17, secured to the plate 16, and the pulley 15, respectively.

A pair of oppositely disposed guide plates, 18—18, are fixed upon the lower face of the plate 16, and suitably spaced apart for receiving and supporting a pair of oppositely disposed jaws, 19—19, and for slid-

ably mounting the same upon the plate. Said jaws each are formed with a semi-circular jaw portion 20, providing a clamping annulus between which the screw cap 5 of a jar is inserted. These jaws each are flared outwardly at their receiving end terminating with an annular roughened portion 22, which is adapted to grip or frictionally engage with the circumferential 10 edge of the screw cap to be operated upon. Each one of the jaws has a pin, 23, projecting at right angles therefrom, and in this case vertically, each through an oblong slot 24, in the plate 16. These pins are 15 connected by a spring 25, which yieldingly urges the two jaws toward each other and enabling the same to expand apart as a cap is inserted between the jaws, and hold the jaws embracingly around the circumferential edge 20 of the cap under sufficient pressure required for threading and tightening the cap upon the bottle or jar, releasable under any excessive pressure after the cap has been 25 properly tightened upon the jar so as to avoid injury to the cap or jar.

This is very essential when applying screw caps, because if undue or excessive pressure were permitted to be applied to the cap effecting a continued threading influence of the cap with its screw jar top or neck would result in breakage or injury to either the cap or jaw. With the device yielding to excessive pressure no care is required on the part of the operator as no undue tightening pressure can be maintained.

The jar with its cap loosely placed thereon can be manually held and moved to bring its cap into engagement between the jaws for applying the final sealing pressure to 40 screw the cap tight upon the mouth of the jar. Such method to many operators would be quite laborious, and also permit them in a rapid handling to jam the cap into the chuck breaking the jars which is dangerous 45 to the operator and the use of the machine in such manner would be prohibited in many localities. In providing a support upon which the jar can be placed and moved into engagement with the chuck a central and 50 alined position of the jar with respect to the chuck jaws which is insured which offers to expedite the operation produces uniform and efficient results upon which reliability as to the proper sealing of the jar can be 55 placed.

The jar is placed upon the holder plate, 26, which normally is in a depressed position below the chuck or cap securing device. This plate has its upper face cupped to provide a pocket for the jars of advantage in 60 readily placing the jars central or in an alined position with the chuck jaw and is mounted upon one end of a plunger 27. The plunger 27 is slidably mounted within a 65 sleeve bracket 28, projecting from the col-

umn 1. A screw 29 is engaged through the sleeve 28, and projects into a spline 30, formed longitudinally in the plunger 27, and is provided to prevent rotation of the plunger.

70

At the lower end of the plunger an annular groove 31 is provided, said groove receiving the end of a crank arm 32 for raising and lowering the plunger.

The crank arm 32 is journaled upon a rod 75 33. 34 represents a second arm connecting with the crank arm 32, and engaging into the yoke end of the arm 34, upon the rod shaft 35, journaled in said column. At the opposite end of the rod shaft 35, I provide 80 a treadle lever 36 for actuating the rod shaft, and parts connected therewith to raise the plunger 27. A spring 37, fixed to the column 1, and crank arm 34, provides the proper tension for returning the parts to 85 their normal position as released by the treadle.

This bottle or jar supporting means enables the operator to quickly and conveniently present the bottle and its screw 90 cap in an alined position with the jaws of the chucking device so as to be readily inserted between said jaws for applying the final sealing pressure to the screw cap and is preferably limited in its upward motion 95 to prevent the cap and its jar from being unduly pressed between the jaw support and the plate 16, to avoid breakage. The jar support is non-rotatable, and thus is stationary at all times, rendering it more convenient 100 to the operator for inserting or removing the jars and centering them with the cap securing devices. The jars are capped after being filled and are placed in an upright position upon non-rotatable supports, 105 so that there is no occasion for spilling any of the contents.

Having described my invention, I claim:

1. In a machine of the class described, a frame, a vertically movable non-rotatable 110 bottle support mounted upon said frame, means for elevating said support, a rotatable bottle cap gripping chuck journaled upon said frame above said bottle support, comprising a jaw supporting plate, a pair of 115 opposing semi-circular jaws slidably mounted in guide-ways on one face of said plate, for engaging a jar cap therebetween, and a spring connecting with said jaws for yieldingly forcing said jaws toward each other. 120

2. In a machine of the class described, a frame, a vertically movable non-rotatable bottle supporting table mounted upon said frame, said table being recessed to receive and sustain a capped jar in an upright position, means for elevating said table, a rotatable jar cap gripping chuck journaled upon said frame above the table, comprising a 125 jaw supporting base member, a pair of semi-circular oppositely disposed jaws movable 130

radially upon said member, each jaw having a flaring cap receiving surface terminating with a roughening surface for embracing and frictionally engaging with the jar cap when the cap is moved into engagement therewith between the jaws, and means for yieldingly urging the jaws toward each other.

In witness whereof, I hereunto subscribe my name, as attested by the two subscribing 10 witnesses.

WALTER BUZATT.
